UNITED STATES PATENT OFFICE.

CLAUDE E. BOWERS, OF LOS ANGELES, CALIFORNIA.

WIRE PACKAGE-HOLDING DEVICE.

Application filed January 4, 1926. Serial No. 79,183.

This invention relates more specifically to a device for holding packaged materials in immovable relation to hollow paper rolls.

A main object of the invention is to provide a device formed of a single piece of wire bent so as to securely hold articles within the openings of hollow paper rolls against displacement.

A further object is to provide a device that will not injure or mutilate the paper of the roll to which it is secured in any manner.

A still further object is to provide a simple device, economical of manufacture, and that may be easily secured to or removed from paper rolls.

Further objects and advantages will be apparent from the following specification, reference being had to the accompanying drawings in which:

20 Fig. 1 is a longitudinal section of one end of a hollow paper roll showing the package holding device secured thereto.

Fig. 2 is a plan view showing the device applied to a roll, the packages of material being omitted therefrom.

Fig. 3 is a perspective view of the device.

Fig. 4 is a detail perspective view of the device with packages mounted therein, a portion of a paper roll to which the device is secured being shown.

Fig. 5 is a detail perspective view of the roll engaging end of a modified form of the device.

Referring now to the drawings 5 designates the package holding device which is preferably formed of a single length of wire of a sufficiently heavy gauge to prevent accidental deformation during handling. In the formation of the device a vertically disposed member 6 is provided, the distance between its ends equalling the combined length of the packages of materials that are to be mounted in the holder. The lower end of member 6 is bent at right angles thereto in the form of a package supporting loop 7, and its upper end is bent at substantially right angles thereto to form a package engaging portion 8, its length being substantially one-half the diameter of the opening 9 of the paper roll 9 to which the device is attached.

50 The wire is again bent at the end of portion 8 at right angles thereto to form a portion 11, of a length equal to the portion 8, the two portions forming a right angle and 55 serving as a support for the packaged articles when placed between said portions and the

lower looped portion 7, as shown in Fig. 4.

In order to form a means for suspending the device within the opening 9 of the roll, the end of portion 11 is bent to form a vertical portion 12, the upper end being bent horizontally as at 13, and again bent downwardly as at 14 in parallel rotation to portion 11 to form a clamping jaw 15. The extreme end of portion 14 is bent upwardly and at an angle to said portion to form a portion 16 that acts as a wedge when portion 14 has been inserted between the windings of the paper roll.

In securing the package holding device to a roll of roofing paper, the operator after the winding of the roll is completed takes a packages of nails 17, and a can of roofing cement 18, such articles being used by the workmen when laying roofs, and places the same between the loop 7 and the horizontally disposed portions 8, 11. The device with the packages secured thereto is then inserted within the roll opening 9, as shown in Figs. 1 and 4, and the operator forces the member 14 of the clamping jaw 15 downwards between two adjacent windings of the roll, the inner member 12 of the jaw engaging the cylindrical surface of the opening 9 thereby firmly clamping the laps of the paper therebetween, the distance between the jaw members 12 and 14 being slightly less than the thickness of about five laps of paper. The wedge portion 16, acts as an additional safeguard in the prevention of the accidental detachment of the device from the roll during a handling operation. By forming a clamping jaw at the upper end of the device above the package supporting members 8 and 11 the device will be supported below the end surface of the roll, thereby protecting the upper end of the package adjacent the clamping jaw from injury.

In Fig. 5, a modified form is illustrated which is substantially the same as the form heretofore described with the single exception of the clamping jaw. In this form the end of portion 11 is bent downwardly to form a roll engaging portion 20, its end 21 being flattened to facilitate its insertion between the roll laps. In order to prevent an accidental disengagement of the roll engaging portion 20 the said portion is bent intermediate its ends to form a curved or "humped" portion as at 22, that will tend to firmly hold the roll engaging member 20 in engagement with the roll.

It will be noted that when the device is inserted within the opening 9 of the roll that the vertical portion 6 will engage the peripheral surface of the said opening, and as the diameter of the packages is about equal to the diameter of the roll opening, the device when the packages are in place will be held in frictional engagement with the wall of the opening, and thus tend to prevent any accidental movement.

What I claim is:

1. A device for holding packages in hollow paper rolls comprising a single length of wire having a vertically disposed body portion, the ends of said portion being bent at substantially right angles thereto to form package engaging and supporting portions, the wire beyond the end of one of said engaging portions being bent upwardly and

then downwardly and disposed in a plane 20 parallel to the body portion to form a roll engaging end.

2. A device of the class described comprising a single length of wire bent to form a vertically disposed body portion, one end of said body portion being bent at right angles into a looped form, the opposite end being bent into right angled portions disposed at right angles to the body portion, the looped and right angled portions forming supports 30 for packages disposed therebetween, and a clamp portion formed on the outer end of said right angled portions, one member of said clamp forming a roll engaging means.

In witness that I claim the foregoing I have hereunto subscribed my name this 19th day of December, 1925.

CLAUDE E. BOWERS.
